(57) **CLAIM**

The ornamental design for a loveseat, as shown and described.

DESCRIPTION

FIG. 1 is a front perspective view of a loveseat in accordance with the invention;

FIG. 2 is a front view of the loveseat of FIG. 1;

FIG. 3 is a rear view of the loveseat of FIG. 1;

FIG. 4 is a right side view of the loveseat of FIG. 1;

FIG. 5 is a left side view of the loveseat of FIG. 1;

FIG. 6 is a top view of the loveseat of FIG. 1; and,

FIG. 7 is a bottom view of the loveseat of FIG. 1.

The broken lines in the figures illustrate the portions of the design that form no part of the claimed design.

1 Claim, 7 Drawing Sheets

FIG. 2

FIG. 3

FIG. 4

FIG. 5

FIG. 6

FIG. 7
